UNITED STATES PATENT OFFICE.

EDWARD HYMAN, OF NEW YORK, N. Y., ASSIGNOR TO SCHNEIDER & HYMAN, OF NEW YORK, N. Y., A COPARTNERSHIP COMPOSED OF KENNETH SCHNEIDER AND EDWARD HYMAN.

DESIGN FOR A RING.

Application filed October 25, 1922. Serial No. 4,086. Term of patent 3½ years.

To all whom it may concern:

Be it known that I, EDWARD HYMAN, a citizen of Russia, residing in the borough of Manhattan, of the city of New York, in the State of New York, have invented a new, original, and ornamental Design for Rings, of which the following is a specification, reference being had to the accompanying drawing, forming a part hereof.

The figure is a perspective view of a ring showing my new design.

I claim the ornamental design for ring, as shown.

This specification signed this 17th day of October, 1922.

EDWARD HYMAN.
